Application April 16, 1949, Serial No. 87,928

8 Claims. (Cl. 58—21.14)

1

This invention relates to alarm devices for use as an accessory to and in combination with any conventional clock mechanism.

Clock alarms are, of course, old; but all those of which we are aware require a tedious setting operation and, for that reason are unsuited to the principal purposes of the present invention. For instance, to set a conventional clock alarm, one must rotate a setting knob while observing the position of a hand on a setting dial, and then the release must be set so that when the alarm time arrives the alarm is free to operate. Consequently, conventional clock alarms are unsuited for uses requiring an instantaneous and simple setting operation such as for a therapeutic treatment or cooking.

Also, it often happens that a person desires to sleep a while longer after first awakening, but is afraid to fall asleep again for fear of oversleeping. On the other hand, the intricacies of setting a conventional clock alarm are so great that a sleepy person would lose any desire for further sleep after setting or resetting a conventional clock alarm.

It is therefore among the objects of this invention to provide an alarm device which may be instantly set with a minimum of effort.

A further object is to provide an alarm mechanism which normally is out of operative engagement with the clockworks, but which may be so operatively engaged by a quick, simple operation and will provide an alarm at any predetermined time after such engagement.

A further object is to provide an alarm setting and actuating device in the operation of which the user does not have to observe the time indicated by clock hands.

Another object is to provide an alarm setting and actuating device which requires no alarm release element. For instance, it is well known that many people, after setting an alarm, forget to operate the release, with the result that no alarm is produced when the alarm time arrives.

Further objects and advantages subordinate to the above stated general objects will appear hereinafter.

Inasmuch as our invention may be carried out by various specific physical embodiments, we do not wish to limit the broader scope of the invention to any particular detailed arrangement, except as may be indicated by the annexed claims. However, for explanatory purposes, we shall now describe certain embodiments of the invention by reference to the accompanying drawings, wherein:

Fig. 1 is a side elevation of an alarm clock, with a portion of the casing broken away to expose inner parts to view;

Fig. 2 is a plan view taken on line 2—2 of Fig. 1;

2

Fig. 3 is an enlarged section taken on line 3—3 of Fig. 1;

Figs. 4 and 5 are enlarged fragmentary views taken on lines 4—4 and 5—5, respectively, of Fig. 3;

Fig. 6 is a view taken on line 6—6 of Fig. 5;

Fig. 7 is a fragmentary side view of a modified form of the invention, with some parts shown in section;

10 Fig. 8 is like Fig. 7, except that it shows the parts in another position;

Fig. 9 is a side elevation, with some parts in section, of a further modification;

15 Fig. 10 is a front elevation of another embodiment;

Fig. 11 is an enlarged front elevation of the device of Fig. 10 with the dial and hands removed;

20 Fig. 12 is a fragmentary view like Fig. 11 except that parts are shown in another position;

Figs. 13, 14 and 15 are sections taken, respectively on lines 13—13, 14—14, and 15—15 of Fig. 11; and

25 Fig. 16 is a fragmentary elevation of a further modification.

In general the invention is carried into practice by providing an alarm mechanism, which may or may not be the ordinary alarm unit of a conventional alarm clock, and provide an alarm actuating means which is normally out of operative engagement with the clockworks, but which may be brought into such engagement by an extremely simple and instantaneous operation. Such engagement automatically sets the alarm to release at any predetermined future time. It is our preference to have this actuating means take the form of a rack which, by ratchet means, may be engaged with the center shaft of a clock, or with the first wheel or any other part of the time mechanism. The rack is moved into such engagement by a manually operable knob exteriorly of the clock casing. When our invention is employed as an auxiliary to the conventional alarm system of a clock, the operation which engages the actuating means with the clockworks also serves to isolate the conventional alarm release mechanism of the clock for the predetermined period.

50 Referring now to the drawings, we show at 5 a conventional alarm clock casing, within which a frame 6 supports the clock mechanism 7. Since such clock mechanisms are well known in the art, no detailed description of the conventional elements is necessary.

55 For instance, such a clock mechanism has a driven center shaft 10 on the outer end of which the minute hand M is mounted and which indirectly drives the hour hand H. This shaft makes one complete revolution every hour.

60 The conventional alarm system of a clock

typically includes a governor 14 fixed on a shaft 15 carrying a gear 16 driven by a gear 17 operated by the alarm spring 18 through the usual gear train. The alarm clapper, not shown, is operatively connected to the spring through said gear train so that when movement of the governor is arrested, the alarm is inoperative.

A resilient latch arm 20 has a pointed outer end 21 which normally projects into the path of rotation of the governor to arrest movement of the latter. The latch arm is normally held in such governor arresting position by the inner end 23 of the hub 24 of a gear 25, which gear is slidably and rotatably mounted on a setting shaft 27. The outer end portion of the hub is hollow and has a cam face 29 on its outer end to engage the radial arm 31 of a collar 30 fixed on the right hand end of setting shaft 27. In setting the conventional alarm, the shaft 27 is rotated to advance the radial arm 31 with respect to the low point of the cam face; and when the gear 25 rotates, in response to the time mechanism, until the low point of the cam face comes into register with the radial arm 31, the gear 25 will move outwardly on its shaft, allowing the latch arm 20 to flex outwardly to move its end 21 out of the path of movement of the governor. The conventional alarm system is then released to create the alarm.

Gear 25 is operatively connected to the hour hand operating gear train through pinion 35 mounted on the stub shaft 36, which shaft also carries gear 37 meshing with a pinion 38 on shaft 10. The hour hand H is operatively connected to shaft 10 through gear train 38, 37, 35 and 41.

For locking the latch arm 20 when it is desired to render it inoperative regardless of the relative position of the cam face 29 and radial arm 31, a lever 45 is pivoted to the clockwork frame 6 at 46 and has a cam element 47 which engages between the frame 6 and a washer 48 carried on the end of a slide bar 49 whose opposite end is fixed to the latch arm 20 between the ends of the latter. In the position shown, the cam is out of engagement with the washer, thus permitting the slide bar to move axially and in turn permitting the latch arm to swing away from the frame 6 by virtue of its own resiliency when the cam relief 29 moves into register with the radial arm 31.

Thus far we have merely described the alarm system, and part of the time system, of a conventional alarm clock of the "Big Ben" type, to which we make no claim of invention, except in combination with the feature now to be described.

We pivot an arm or lever 60 to the frame 6 at 61 and provide a spring 62 to urge said arm upwardly. Adjacent the outer end of said arm, we provide a somewhat depending finger 65 which, when the arm 60 is swung downwardly, moves into the path of rotation of the governor to arrest rotation of the latter.

On shaft 10 we fix a ratchet 66 and rotatably mount a ratchet-gear 67 urged into engagement with ratchet 66 by a spring 68. Shaft 10 has a portion of squared cross section fitting in the ratchet 66, while ratchet-gear 67 has a circular axial opening 67a to receive the squared portion of the shaft.

Pivots secured to the outer end of arm 60, at 69, we provide a depending rack arm 70, along the lower end portion of which we provide a row of rack teeth 71 meshing with ratchet gear 67.

For instance, if the ratchet gear 67 has 12 teeth, we provide twelve rack teeth 71, so that one complete revolution of the ratchet gear moves the rack a distance equal to the length of the toothed area. The rack arm is urged outwardly, or to the left in Fig. 1, about its pivot, by a spring 75, so that the rack teeth are always resiliently held in engagement with the gear 67.

Thus, when arm 60 is swung downwardly, the auxiliary alarm is automatically set by the rack arm rotating the ratchet gear to the desired extent, and the governor is maintained arrested by the finger 65 until the rack moves over the ratchet gear sufficient to free the finger from the governor, which then permits the alarm signal to be given.

To disengage the latch arm portion 21 from the governor, in order to enable our auxiliary alarm actuating means to operate, the arm 60 carries a depending projection 80 having a wedge-shaped lower end to enter between the latch arm and the frame 6 when the arm 60 is swung downwardly. This springs the outer end of the latch arm away from the casing and thus allows rotation of the governor when arm 60 moves upwardly far enough to free its finger 65 from engagement with the governor. The projection 80 is longer than the finger 65.

To depress the arm 60, we provide an opening 98 in the clock casing top wall and provide a screw 91 threaded into the arm 60, and a stop 92 is engageable by the inner end of the screw. We also provide an upright plate 94 exteriorly of the clock casing, upon which we show suitable indicia in minutes positioned for registry with the outer end of the screw.

In operation, assuming that it is desired to set the auxiliary alarm to give an alarm signal one-half hour hence, the screw 91 will be adjusted so that it will permit enough downward movement of the rack 70 to rotate the ratchet gear 67 a half revolution before the inner end of the screw engages the stop 92. This downward movement of the arm 60 causes finger 65 to move

into the path of movement of the governor, and also flexes the latch arm outwardly, so that when the ratchet gear has rotated clockwise a half turn the finger will first move out of the path of the governor, allowing the alarm signal to commence. The signal will continue until the projection 80 moves free of the latch arm, which permits the latch arm to flex inwardly to arrest movement of the governor and stop the alarm.

While we have described the rack as being operated by the center shaft, it will be apparent that any other driven part of the time mechanism may be used to engage the rack. We have merely chosen the center shaft because it rotates a complete revolution every hour and therefore allows a greater latitude of movement of the rack.

Referring now to Figs. 7 and 8, we show an embodiment wherein the parts are as described in connection with Figs. 1 to 6, inclusive, except that in lieu of the manual actuating screw 91 for depressing the arm 60, we show an arrangement whereby the alarm may be set for, say, a fifteen minute period by once pressing inwardly upon a setting button, or may be set for thirty minutes by pressing twice upon the setting button, etc., thus eliminating the necessity of any adjustment of the manual actuating means.

Here the numeral 60a denotes the setting arm, which is like arm 60 previously described except that at its outer end it has a curved portion 100

presenting ratchet teeth 101. A leaf spring 103 is fixed to the clockwork frame 6 as by a split screw 104, and has an upturned outer end presenting a transverse slot 105. A toggle having legs 106, 107 and 108 is pivotally attached to the inner end of a push rod 110 carrying a push button 111 on its outer end. Toggle leg 106 is pivoted at one end 112 to ears 113 and at its other end to leg 108, while leg 107 is pivoted at its inner end to leg 108 and slides at its other end along the top surface of the spring 103 through slot 105. A stop 115 limits downward movement of the spring, while a stop 116 limits its upward movement. A cross pin 117 limits outward movement of the push rod 110, and a coil spring 118 urges the push rod outwardly.

The ratchet teeth 101 are spaced apart so as to represent, for instance, fifteen minute periods. That is, when the arm 60a is pushed downwardly the distance of one tooth, the rack 70 moves the ratchet gear 67 enough to require the time shaft 10 to rotate through a fifteen minute period to return the rack. Thus, if it be desired to set the alarm to ring thirty minutes hence, two inward pushes on the button 111 will accomplish such setting. On each push, the toggle is first operated to cause toggle leg 107 to engage a ratchet tooth 101 and then continued inward pressure on the button flexes the spring enough to swing the arm 60a downwardly until the spring 103 engages stop 115 (Fig. 8) which downward movement causes rack arm 70 to rotate the ratchet gear 67 clockwise. Release of pressure on the button allows the spring 103 and spring 118 to return the parts to the position of Fig. 7. Thus each consecutive push on the button sets the alarm for an additional fifteen minute period hence.

In Fig. 9 we illustrate one of the various ways in which the arrangement of Figs. 1-6, or 7-8, may be employed to actuate an electric alarm. Here, instead of the parts 21 and 65 before described, arm 60b has an extension 125 disposed, when in its uppermost position, to engage a toggle arm 126 to move the arm above center and cause it to raise a spring loaded switch arm 127 and thus actuate a switch 128 to close an electrical circuit through wires 129, 130 to an electric alarm, such as a bell, not shown. The toggle arm 126 may be returned to off position (Fig. 9), and thus stop the alarm, by depressing a spring loaded push rod 132. Adjusting screw 91a when manually pushed downwardly to stop 92a operates lever 60b.

In Figs. 10-15, we show a further modification of our invention, illustrated as applied to a conventional alarm clock mechanism such, for instance, as a "Little Ben" clock.

The numeral 200 indicates the front frame plate holding the clockworks, to which the partial overlying plate 201 is attached by screws 203. 210 is the minute hand carrying or center shaft operated by the time mechanism to rotate clockwise a complete revolution once every hour. The minute hand is denoted 211. The hour hand 220 is indirectly driven from shaft 210 through the train of gears 212, 213, 214 and 215.

A gear 225, driven from gear 214 carries a hub flange 226 socketed to receive a collar 228 on the alarm setting shaft 229. The collar has a radial arm 230 which rides over the eccentric cam face 231 of the flange 226. The shaft 229 and collar 228 remain rotatably stationary after once being set, and when the gear 225 rotates in response to the time mechanism to the point at which the arm 230 reaches the low point of the

cam face 231, the conventional alarm is released to operate because of the following mechanism: a resilient arm 235 fixed at its inner end to the casing by screw 236, bears outwardly against the inner face of gear 225, thus holding the cam face 231 in engagement with the arm 230. The arm 235 has an inwardly bent outer end portion 235a which normally engages a pin 233 projecting from the side of the alarm clapper 240 which is secured on the clapper operating shaft 241. The clapper strikes against the metallic clockworks housing 242. Thus, when the gear 225 is rotated to a point where the radial arm 230 reaches the low point of said cam face 231, the resilient arm 235 pushes the gear 225 axially outwardly on the shaft 229, allowing the arm 235 to flex outwardly far enough to permit its free end to move out of engagement with the pin 233, allowing the clapper to operate. 245 is the manual alarm lock which, when pulled out, releases the described alarm mechanism to operate when the alarm point is reached.

Up to this point in the description of the mechanism of Figs. 10-15, we have merely described essential elements of a conventional time and alarm clock mechanism, which are so well understood in the art as to require no further detailed description. We shall now describe our auxiliary alarm arrangement of this adaptation and its cooperation with those conventional parts.

An arcuate lever 250 is pivoted between its ends to the frame plate 200 by a screw 252 and has a slot 253 to receive a movement limiting screw 254. A pawl 260 is pivotally connected to the outer end 35 of the lever by screw 261. The outer end of the pawl is disposed to be normally out of engagement with a ratchet-toothed gear 265 mounted on a shaft 266. Gear 265 fixedly carries a segmental gear or rack 268 whose teeth 269 mesh with a gear 270 rotatably mounted on a shaft 271; and gear 270 has ratchet teeth 270a on its underside which engage side teeth 272 on a gear 273, the peripheral teeth of the latter gear meshing with gear 212 on shaft 210. A spring arm 275, fixed at one end to the frame plate 200 by screw 276, bears at its outer end against the end of gear 270 to yieldably hold its ratchet-toothed under face 270a in engagement with teeth 272 on the outer face of a gear 273.

A spring 280 urges the outer end of the lever 250 towards gear 268 to such extent that screw 254 normally abuts the right-hand end of slot 253 as a stop, while a spring 282 bears against the inner end 283 of the pawl to urge the outer end of the pawl towards the ratchet gear 265, although normally the beveled outer end of the pawl is held out of engagement with said gear by a fixed stop pin 285 until the pawl is pulled to the right enough to permit engagement of the pawl with the ratchet gear.

A leaf spring 290 (Fig. 10), fixed at one end to the outer clock casing 292, carries a push button 293 at its outer end and a depending pin 294 which engages the flattened inner end 290a of the lever 250, so that when the button is pushed downwardly once, it engages and depresses the inner end of the lever, causing the lever to swing about its pivot and draw pawl 260 to the right to engage it with the ratchet gear 265 and rotate that gear counterclockwise to the predetermined extent desired. Rotation of that gear causes the segmental gear 268 to rotate the ratchet gear 270 clockwise. Upon release of the push button, the spring 280 returns the lever and pawl to the original position. As will become obvious, two or

more successive pushes upon the button will move the gear 268 commensurately farther in a counterclockwise direction. The extent to which the gear 268 is thus rotated counterclockwise determines the period to elapse before the alarm will be released; since to accomplish such release the center shaft, operating clockwise, must, through gears 273, 270, rotate gear 268 clockwise to its starting position.

Assuming that the conventional alarm mechanism is not set to release simultaneously with the release of the auxiliary alarm, it is of course necessary to provide means, operable in consonance with the setting of the auxiliary alarm, to release the alarm clapper so that it will be free to operate when the auxiliary alarm time arrives. The mechanism which we here provide for this function will now be described.

A plate 300 is pivoted to the frame plate 260 as by screw 301, and the plate 300 carries a wedge-shaped projection 303 tapering to a point at its outer end disposed to enter wedge-like between the resilient locking arm 235 and the frame plate 260 to spring or flex said arm out of arresting engagement with the clapper. The plate 300 also carries an inwardly projecting pin 310 which moves into the path of the clapper as the projection 303 springs the arm 235 outwardly to release the clapper. To swing the plate for accomplishing this function, we provide the plate with an arcuate projection 315 having an inner cam face, and provide a depending pin 317 on the gear 268, so that upon the initial counterclockwise movement of that gear, the pin cams the projection 315 outwardly, swinging the plate 300 as described. Further counterclockwise rotation of said gear holds the projection so cammed outwardly but does not move it farther outwardly since the projection is curved about the radius of movement of the pin. A spring 318 urges the plate 300 into engagement with pins 235a and 317.

We provide a booster spring 320 which urges the gear 268 clockwise to compensate for any possible drag upon the time mechanism which might be offered by the auxiliary alarm mechanism described.

To visually indicate on the clock dial D how many pushes have been imposed upon the button 293, we provide an arcuate slot 330 in the dial and display suitable spaced indicia therealong, such as "1, 2, 3." And projecting from the front face of the segmental gear 268, we provide a pin 332 which projects into the slot. Thus as the gear 268 is rotated, the pin 332 is moved along the slot.

Operation of this embodiment is as follows:

For explanatory purposes, we shall assume that the conventional alarm mechanism is set to release at a time several hours hence, but that the user wishes to have the auxiliary alarm operate one-half hour hence without the necessity of having to go to the trouble of re-setting the conventional alarm. We shall also assume that the auxiliary alarm mechanism is made so that one push upon the button 293 will move the segmental gear counterclockwise sufficient to require one-quarter hour's operation of the time mechanism to rotate the segmental gear clockwise to starting position.

Thus, to set the auxiliary alarm to operate one-half hour hence, all the user has to do is to push downwardly on the button two consecutive times. This will move the gear 268 counterclockwise in two stages of fifteen minutes each to the position of Fig. 12. Upon the first push upon the

button, the pin 310 will have moved into the path of the clapper to render the latter immovable, and projection 303 will have disengaged the locking arm 235 from the clapper. As soon as the center shaft has been rotated by the clock time mechanism sufficient to denote the elapse of one-half hour, the gear 268 will have been returned substantially to starting position, or far enough to cause the pin 317 to ride over the inner part of the beveled outer end of the cam surface of projection 315. At that point the plate 300 will be permitted to swing under the influence of spring 318 sufficiently to move pin 310 out of the path of the clapper, permitting the latter to commence operation. Upon full return to starting position of gear 268, the beveled projection 303 will completely withdraw from beneath the arm 235, allowing that arm to spring back into arresting engagement with the clapper. Thus the period of the auxiliary alarm will be the time between said movement of pin 310 out of the path of the clapper and the subsequent complete withdrawal of the projection 303 from beneath arm 235.

However, if it be desired to provide for a longer alarm signal, we may use the variational form of locking arm release shown in Fig. 16. Here instead of fixing the projection 303a to plate 300a, we slidably mount the projection in a recess 375 in plate 300a. The projection has a longitudinal slot 376 through which projects a pin 377 carried by the plate. The inner end of the projection has a right angle projection 378 which projects through and moves in a slot 379 in the bottom wall of recess 375. On swinging the plate to the left the pin 377, engaging the end of slot 376, moves the projection under the locking arm, but upon swinging the plate in the reverse direction the pin will move along the slot and allow the projection to remain under the locking arm until it is manually withdrawn by means of the projection 378 which projects from the clock casing to an accessible position.

We claim:

1. An alarm device comprising, in combination with a timepiece having a timeworks and an alarm unit, alarm stopping means controlling the alarm unit, alarm setting and actuating means comprising a member normally disposed out of operative engagement with the timeworks but being movable into operative engagement therewith, and means associated with said member to release the alarm stopping means and to lock the alarm unit in response to movement of said member into operative engagement with the timeworks; said member being operative in response to operation of the timeworks for a predetermined period to release the alarm unit and being operative after a further operation of the timeworks to cause the alarm stopping means to arrest operation of the alarm unit.

2. An alarm device comprising, in combination with a timepiece having a timeworks and an alarm unit, alarm setting and actuating means comprising a member normally disposed out of operative engagement with the timeworks but being movable into operative engagement therewith, means associated with said member to actuate the alarm unit after a predetermined period of operative engagement with the timeworks, manually operable lever means operable to move said member into operative engagement with the timeworks in successive steps of predetermined extent and spring means operably associated with

said lever means to reset the latter means after each of said steps.

3. An alarm device comprising, in combination with a timepiece having a timeworks and an alarm unit, main setting means for the alarm unit, alarm stopping and releasing means operatively associated with the main setting means, auxiliary alarm setting and actuating means comprising a rack normally disposed out of operative engagement with the timeworks, manually operable means for moving the rack into predetermined operative engagement with the timeworks, release means operable by the rack to release the alarm stopping means in response to movement of the rack into operative engagement with the timeworks and locking means operable by the rack to lock the alarm unit in response to movement of the rack into operative engagement with the timeworks; said rack being operable in response to predetermined operation of the timeworks to release the locking means and to disengage said release means from the alarm stopping means.

4. An alarm device comprising, in combination with a timepiece having a timeworks and an alarm unit, main setting means for the alarm unit, alarm stopping and releasing means operatively associated with the main setting means, auxiliary alarm setting and actuating means comprising: a rack gear, ratchet means operatively connecting the rack gear to the timeworks, a pawl normally disposed out of engagement with the rack gear, lever means for moving the pawl into engagement with the rack gear, spring means for moving the pawl out of engagement with the rack gear, a plate swingably mounted on the timepiece, cooperating cam and follower means associated with the rack gear and plate to swing the plate in one direction in response to movement of the rack gear, spring means urging the plate in the opposite direction, means carried by the plate to engage and release the alarm stopping means when the plate is swung in one direction and to disengage therefrom when the plate is swung in the opposite direction, and means carried by the plate to lock the alarm unit when the plate is swung in one direction and to release the alarm unit when the plate is moved in the opposite direction.

5. An alarm device comprising, in combination with a timepiece having a timeworks and an alarm unit, main setting means for the alarm unit, alarm stopping and releasing means operatively associated with the main setting means, auxiliary alarm setting and actuating means comprising: a rack gear, ratchet means operatively connecting the rack gear to the timeworks, a pawl normally disposed out of engagement with the rack gear, lever means for moving the pawl into engagement with the rack gear, spring means for moving the pawl out of engagement with the rack gear, a plate swingably mounted on the timepiece, cooperating cam and follower means associated with the rack gear and plate to swing the plate in one direction in response to movement of the rack gear, spring means urging the plate in the opposite direction, means carried by the plate to engage and release the alarm stopping means when the plate is swung in one direction and to disengage therefrom when the plate is swung in the opposite direction, and spring means cooperating with the rack gear to compensate for any drag imposed on the time-

works by the auxiliary alarm setting and actuating means.

6. An alarm device comprising, in combination with a timepiece having a timeworks and an alarm unit, main setting means for the alarm unit, alarm stopping and releasing means operatively associated with the main setting means, auxiliary alarm setting and actuating means comprising: a rack gear, ratchet means operatively connecting the rack gear to the timeworks, a pawl normally disposed out of engagement with the rack gear, lever means for moving the pawl into engagement with the rack gear, spring means for moving the pawl out of engagement with the rack gear, a plate swingably mounted on the timepiece, cooperating cam and follower means associated with the rack gear and plate to swing the plate in one direction in response to movement of the rack gear, spring means urging the plate in the opposite direction, means carried by the plate to engage and release the alarm stopping means when the plate is swung in one direction and to disengage therefrom when the plate is swung in the opposite direction, and means carried by the rack gear to visually indicate the extent of engagement of the rack gear with the timeworks.

7. In an alarm device, the combination, with a constantly operable timeworks unit, an alarm unit and a main alarm control unit normally maintaining the alarm unit immobile, of auxiliary alarm control means normally out of operative engagement with said units; said means being movable, in a single operation, into alarm immobilizing position, into position releasing said main alarm control unit and into operative engagement with said timeworks unit, and being then operable automatically, in response to operation of the timeworks unit for a predetermined period, sequentially to free the alarm unit for a predetermined period and thence to cause the main alarm control unit to immobilize said alarm unit.

8. In an alarm device having timeworks, an alarm unit, and an alarm control unit operable in response to operation of the timeworks when in operative engagement therewith; said alarm control unit including a rack member mounted for intermittent step-by-step movement into operative engagement with said timeworks, a reciprocal member mounted in position to so actuate said rack member, and spring means cooperating with said reciprocating member to reset the same after each said actuation.
